(57) **CLAIM**

The ornamental design for a insulated container for worms,
as shown and described.

DESCRIPTION

FIG. 1 is a perspective view of the insulated container for worms showing our new design, with a lid set into an opened position and without an internal ice pack at the underneath of the lid which has been omitted for clarity of illustration; FIG. 2 is a front elevational view thereof with the lid set in a closed position;

FIG. 3 is a rear elevational view thereof with the lid set in a closed position;

FIG. 4 is a side elevational view thereof with the lid set in a closed position;

FIG. 5 is a bottom plan view thereof with the lid set in a 180 degree opened position;

FIG. 6 is a top plan view thereof with the lid set in a 180 degree opened position;

FIG. 7 is a front elevational view thereof with the lid set in a 90 degree opened position and provided with a ice pack at the underneath of the lid;

FIG. 8 is a top plan view of the ice pack shown in FIG. 7; and,

FIG. 9 is a side elevational view of the ice pack of FIG. 8. The ice pack has been shown separately in FIGS. 8 and 9 for clarity of illustration.
